UNITED STATES PATENT OFFICE.

DANIEL W. HOGE, OF CHICAGO, ILLINOIS, ASSIGNOR, BY MESNE ASSIGNMENTS, TO BASH OIL AND REFINING COMPANY, OF CHICAGO, ILLINOIS, A CORPORATION OF DELAWARE.

METHOD OF TREATING PETROLEUM.

Application filed June 24, 1916. Serial No. 105,584.

To all whom it may concern:

Be it known that I, DANIEL W. HOGE, a citizen of the United States, residing at Chicago, in the county of Cook and State of Illinois, have invented certain new and useful Improvements in Methods of Treating Petroleum, of which the following is a specification.

The proportion of gasoline recoverable from petroleum is normally fixed with respect to the particular character of the crude oil but has been somewhat increased by cracking the oil according to various methods. These methods most frequently include heating the oil under high pressure and have been a source of annoyance and danger to those refiners who have carried such methods into practical use.

It is an object of my invention to provide a method of treating petroleum vapor to increase the yield of gasoline without the necessity of resorting to high pressure.

A further object is the provision of a method for treating petroleum residues from which the lighter fractions containing the gasoline have been distilled and which are generally known and used as fuel oil, whereby an additional quantity of gasoline may be recovered therefrom.

Further objects and advantages of my invention will be apparent as it is better understood by reference to the following specification when read in connection with the accompanying drawing, in which—

Fig. 1 is a vertical transverse section through an apparatus for carrying out the present method;

Fig. 2 is a plan view of the receptacle for the molten bath;

Fig. 3 is a section on the line 3-3 of Fig. 2, and

Fig. 4 is a section on the line 4-4 of Fig. 2.

Referring to the drawing, a suitable furnace is illustrated comprising outer walls 1 of ordinary brick and inner walls 2 of refractory brick separated by air spaces 3. The chamber formed within the walls 2 is partially filled with inert material 4, preferably sand, clay or the like, upon which

the checker work 5 is supported. A burner 6 is disposed through a suitable opening in the walls of the furnace to supply heat to

the checker work 5, and a suitable flue 15 for the escape of furnace gases is provided. 55

Supported upon the walls 2 and depending into the chamber within the furnace is a receptacle or pan 7 preferably constructed of cast steel of suitable thickness to withstand the strains to which it is subjected. The pan 60 7 may be six feet long and four feet wide but obviously the dimensions may be varied depending upon the desired capacity of the apparatus. Within the pan 7 a bath 8 of molten refractory material, preferably lead, 65 is disposed which may be three inches in depth or sufficient to submerge the pipes 9 which are arranged lengthwise of the pan 7 and are preferably cast integrally therewith. Headers 10 consisting of cast blocks having 70 openings connecting the ends of the pipes 9 form therewith a continuous conduit spaced approximately one-fourth of an inch from the bottom of the pan. The headers 10 are bolted to the sides of the pan 7 and are 75 readily removable so that the interiors of the pipes 9 may be easily cleaned at intervals. One end of the conduit formed by the pipes 9 is connected to a still and the opposite end is connected to a condenser. The still and condenser are of usual construction well-known in the art and are, therefore, not illustrated. A cover 11 consisting of sheet metal and asbestos cement closes the pan 7, 80 an opening 12 being however provided on 85 the cover 11 for the escape of heated air.

In carrying out my method the crude oil is first distilled according to the usual method to remove the lighter fractions including the gasoline, or residues which have 90 been subjected to such treatment are employed. These residues are heated in the still to a temperature sufficiently high to vaporize the heavier fractions which are led to the apparatus above described and 95 allowed to pass through the conduit formed by the pipes 9 at a pressure preferably not exceeding sixteen ounces above atmospheric pressure. The temperature of the lead bath surrounding the pipes 9 is preferably maintained at between 900° and 1100° F., but it 100 may vary between 750° and 1250° F.

The vapor when subjected to this temperature at relatively low pressure is broken up or cracked to form compounds analogous to 105 those present in gasoline and when con-

densed yields a condensate containing liquid in every respect similar to gasoline obtained from the lighter fractions of the crude oil. The gasoline resulting from my method is refined in the usual manner and is then ready for the market.

By the use of my method it is possible to obtain upward to 25% of gasoline from material heretofore useless for this purpose and used principally as fuel oil. It will be readily understood, therefore, that I have succeeded in providing a method of and apparatus for treating petroleum vapor which, though marked by great simplicity is nevertheless capable of vastly increasing the yield of gasoline from the present sources of this valuable fluid. My method may be employed in ordinary refineries in connection with the methods and apparatus now in common use without discarding or changing any of such apparatus beyond connecting my apparatus thereto and my method may be employed as an auxiliary to the well-known methods to increase the yield of gasoline.

The claims of the present application are directed to the action on the vapor which takes place at the abrupt bends as distinguished from the impinging action which is disclosed and claimed in my co-pending application, Ser. No. 236,449, originally filed May 25, 1918 and renewed, August 21, 1923.

I claim:

- 35 1. The method of obtaining gasoline, which consists in vaporizing heavy hydro-carbon oils, causing the vapor to flow slowly at low pressure through and in contact with the walls of a conduit having relatively great length with respect to its cross-sectional area, causing the vapor to frequently and abruptly change its direction of flow through said conduit to prevent the formation of carbon, and heating the walls of the conduit to a temperature sufficiently high to break down the high boiling point compounds of the vapor as it passes through the conduit in contact with the heated walls thereof.
- 40 2. The method of obtaining gasoline which consists in vaporizing heavy hydro-carbon oils, causing the vapor to flow slowly at a pressure not exceeding sixteen ounces above atmospheric pressure through and in contact with the walls of a conduit having relatively great length with respect to its cross-sectional area, causing the vapor to frequently and abruptly change its direction of flow through said conduit to prevent the formation of carbon, and heating the walls of the conduit to a temperature sufficiently high to break down the high boiling point compounds of the vapor as it passes through the conduit in contact with the heated walls thereof.
- 45 3. The method of obtaining gasoline which consists in vaporizing heavy hydro-carbon oils, causing the vapor to flow slowly at a pressure not exceeding sixteen ounces above atmospheric pressure through and in contact with the walls of a conduit having relatively great length with respect to its cross-sectional area, causing the vapor to frequently and abruptly change its direction of flow through said conduit to prevent the formation of carbon, and heating the walls of the conduit to a temperature sufficiently high to break down the high boiling point compounds of the vapor as it passes through the conduit in contact with the heated walls thereof.
- 50 4. The method of obtaining gasoline which consists in vaporizing heavy hydro-carbon oils, causing the vapor to flow slowly at a pressure not exceeding sixteen ounces above atmospheric pressure through and in contact with the walls of a conduit having relatively great length with respect to its cross-sectional area, causing the vapor to frequently and abruptly change its direction of flow through said conduit to prevent the formation of carbon, and heating the walls of the conduit to a temperature sufficiently high to break down the high boiling point compounds of the vapor as it passes through the conduit in contact with the heated walls thereof.
- 55 5. The method of obtaining gasoline which consists in vaporizing heavy hydro-carbon oils, causing the vapor to flow slowly at a pressure not exceeding sixteen ounces above atmospheric pressure through and in contact with the walls of a conduit having relatively great length with respect to its cross-sectional area, causing the vapor to frequently and abruptly change its direction of flow through said conduit to prevent the formation of carbon, and heating the walls of the conduit to a temperature sufficiently high to break down the high boiling point compounds of the vapor as it passes through the conduit in contact with the heated walls thereof.
- 60 6. The method of obtaining gasoline which consists in vaporizing heavy hydro-carbon oils, causing the vapor to flow slowly at a pressure not exceeding sixteen ounces above atmospheric pressure through and in contact with the walls of a conduit having relatively great length with respect to its cross-sectional area, causing the vapor to frequently and abruptly change its direction of flow through said conduit to prevent the formation of carbon, and heating the walls of the conduit to a temperature sufficiently high to break down the high boiling point compounds of the vapor as it passes through the conduit in contact with the heated walls thereof.
- 65 7. The method of obtaining gasoline which consists in vaporizing heavy hydro-carbon oils, causing the vapor to flow slowly at a pressure not exceeding sixteen ounces above atmospheric pressure through and in contact with the walls of a conduit having relatively great length with respect to its cross-sectional area, causing the vapor to frequently and abruptly change its direction of flow through said conduit to prevent the formation of carbon, and heating the walls of the conduit to a temperature sufficiently high to break down the high boiling point compounds of the vapor as it passes through the conduit in contact with the heated walls thereof.

3. The method of obtaining gasoline, which consists in vaporizing heavy hydro-carbon oils, causing the vapor to flow slowly at low pressure through and in contact with the walls of a conduit having relatively great length with respect to its cross-sectional area, causing the vapor to frequently and abruptly change its direction of flow through said conduit, and heating the walls of the conduit to a temperature of between 75° and 1250° F. to break down the high boiling point compounds of the vapor as it passes through the conduit in contact with the heated walls thereof.

4. The method of obtaining gasoline which consists in vaporizing heavy hydro-carbon oils, causing the vapor to flow slowly at a pressure not exceeding sixteen ounces above atmospheric pressure through and in contact with the walls of a conduit having relatively great length with respect to its cross-sectional area, causing the vapor to frequently and abruptly change its direction of flow through said conduit, and heating the walls of the conduit to a temperature of between 75° and 1250° F. to break down the high boiling point compounds of the vapor as it passes through the conduit in contact with the heated walls thereof.

5. The method of making gasoline which consists in vaporizing heavy hydro-carbon oil, causing the vapor to flow very slowly at low pressure through and in contact with the walls of a conduit having relatively great length with respect to its cross-sectional area, the conduit having a large number of abrupt return bends so that the vapor not in contact with the surface of the conduit will be caused to come into contact therewith to prevent the formation of carbon, and maintaining the conduit at a temperature sufficiently high to crack the vapors of the heavy compounds into gasoline.

6. The method of making gasoline which consists in vaporizing heavy hydro-carbon oil, causing the vapor to flow very slowly at low pressure through and in contact with the walls of a conduit having relatively great length with respect to its cross-sectional area and divided into a series of unobstructed passages successively connected by abrupt return bends so that the vapor not in contact with the surfaces of the unobstructed passage portions will be caused to come in contact therewith to prevent the formation of carbon, and maintaining the conduit at a temperature sufficiently high to crack the vapors of the heavy oil into gasoline.
